UNITED STATES PATENT OFFICE.

ISADORE JOSEPH LEVY, OF NEW YORK, N. Y.

DESIGN FOR A HAND-BAG.

40,566.

Specification for Design.

Patented Mar. 8, 1910.

Application filed January 8, 1910. Serial No. 537,095. Term of patent 3½ years.

To all whom it may concern:

Be it known that I, ISADORE JOSEPH LEVY, a citizen of the United States, and a resident of New York, in the county of New York and State of New York, have invented a new, original, and ornamental Design for Hand-Bags, of which the following is a specification, reference being had to the accompanying drawings, forming a part hereof.

The figure is a view in elevation of a hand bag showing my design.

I claim:

The ornamental design for a hand bag as shown.

ISADORE JOSEPH LEVY.

In presence of—

LESTER F. DITTENHOEFER,
GERTRUDE K. BRENNAN.
